(57) **CLAIM**

The ornamental design for a battery box, as shown and described.

DESCRIPTION

FIG. 1 is a perspective view of my new design for a battery box;

FIG. 2 is a front view thereof;

FIG. 3 is a rear thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of my new design for a battery box;

FIG. 9 is a front view thereof;

FIG. 10 is a rear thereof;

FIG. 11 is a left side view thereof;

FIG. 12 is a right side view thereof;

FIG. 13 is a top plan view thereof; and,

FIG. 14 is a bottom plan view thereof.

The battery box is shown with symbolic breaks in its length and height in FIGS. 8-14. The appearance of any portion of the article between the dash-dot break lines forms no part of the claimed design.
